UNITED STATES PATENT OFFICE.

VICTOR M. TYLER, OF NEW HAVEN, CONNECTICUT, ASSIGNOR TO THE SENTINEL MFG. CO., OF NEW HAVEN, CONNECTICUT, A CORPORATION.

TIME-CONTROLLED GAS-BURNING APPARATUS.

Application filed November 23, 1926. Serial No. 150,234.

This invention relates to improvement in time-controlled gas-burning apparatus and particularly to that class of time-controlled gas-burning apparatus employing a so-called "pilot-light" for igniting the gas emerging from the burner when it has been automatically turned on by a timing-mechanism.

As heretofore constructed, time-controlled gas-burning apparatus of the class just above described have constituted a grave source of danger to persons and property, since, should the pilot-light become extinguished for any reason, the gas emerging from the burner, when the timing-mechanism acts to automatically turn it on, will not be ignited as intended, but will flow out into the atmosphere and possibly cause asphyxiation, an explosion, or a fire.

The object of this invention is to provide a time-controlled gas-burning apparatus in which the automatic turning-on of the gas by the timing-mechanism proper will be automatically forestalled and prevented, should the pilot-light become extinguished for any reason.

With this object in view, my invention consists in a time-controlled gas-burning apparatus characterized by its provision with a thermostat mounted in position to be affected by the heat developed by a pilot-light and adapted to operate a stop-member located in position to engage a moving part of the timing-mechanism proper, so as to automatically suspend the action thereof, should the pilot-light become extinguished.

My invention further consists in a time-controlled gas-burning apparatus characterized as above and having certain other details of construction as will be hereinafter described and particularly pointed out in the claims.

In the accompanying drawings:

Fig. 1 is a view mainly in elevation and partly in section of a time-controlled gas-burning apparatus constructed in accordance with my invention;

Fig. 2 is a transverse sectional view on the line 2—2 of Fig. 1; and

Fig. 3 is a view, corresponding to Fig. 1, partly broken away, and showing a modified form which my invention may assume.

In carrying out my invention, as herein shown, I employ a gas-burner 5 provided with the usual series of nipples 6 and receiving its supply of gas from a feed-pipe 7,

in which latter I interpose a control-valve 8 adapted to be operated by a timing-mechanism herein generally designated by the numeral 9.

The particular nature of the timing-mechanism employed as a feature of my improved apparatus is immaterial, so long as it is adapted to automatically turn on a supply of gas to the burner 5 in the well-known manner. For this reason, the timing-mechanism is not illustrated in detail in the accompanying drawings, but as shown is of the general type illustrated in United States Patent No. 1,609,432 to John A. Scott, timing mechanism, dated December 7, 1926, 70 which is adapted to automatically perform the functions of turning on the gas and subsequently turning it off, though, as above stated, my invention is only concerned with the phase of its operation in which the gas is turned on.

As outlined in the drawings, the timing-mechanism consists of a dial 10 mounted upon the front face of the timing-mechanism casing 11 and swept by two setting-pointers 12 and 13, the setting of which determines the length of time which shall elapse before the gas-valve 8 is automatically operated. The timing-mechanism also embodies a time-train of standard form, which includes the 85 usual balance-wheel 14, hair-spring 15, and escapement-lever 16.

Upon a bracket 17, within the casing of the timing-mechanism and in position to engage the balance-wheel 14, I mount a yielding 90 stop-member 18 in the form of a flat spring which constantly exerts itself to engage the periphery of the balance-wheel 14, so as to check its oscillations and hence completely stop the time-train.

For the purpose of normally holding the stop-member 18 out of engagement with the balance-wheel, so as to permit the time-train to run as intended, I employ a transmitting rod 19 reciprocating within a hollow thermostat housing-tube 20 projecting outward from the casing 11 to a position closely adjacent to the burner 5 and directly over a pilot-light jet 21, which latter receives its supply of gas through a tube 22 connected into the feed-pipe 7 as shown. Within its outer end the housing-tube 20 encloses a thermostat 23, consisting of a cylinder of selenium, or other suitable material, having a relatively high coefficient of thermal ex-

pansion, which, as will hereinafter appear, acts when heated, through the medium of the transmission-rod 19, to force the stop-member 18 out of engagement with the balance-wheel 14.

Under normal conditions, the pilot-light jet will be lighted and the thermostat 23 thereby kept heated, with the result that the stop-member 18 will be held clear of the balance-wheel 14, so as not to interfere with the running of the time-train, which latter, after the lapse of a predetermined time, will act through the valve 8 to turn on the supply of gas to the burner 5, where, upon emerging from the nipples 6, it will be ignited by the pilot-light.

If, however, the pilot-light jet 21 should become extinguished for any reason, the thermostat 23 will cool, and hence contract, whereby the stop-member 18 will be permitted to assert itself and engage the periphery of the balance-wheel 14, and through it completely stop the running of the time-train, and thus effectively prevent the gas from being turned on and its ultimate escape into the atmosphere. Re-lighting the pilot-light jet will serve to heat the thermostat 23 and positively move the yielding stop-member 18 out of engagement with the balance-wheel of the time-train, which is then free to resume its operation.

It will be apparent that the type of thermostat employed may vary widely and, therefore, I wish to have it understood that I do not limit myself to the type shown.

In the modified form of my invention shown in Fig. 3, I employ a transmitting-member in the form of a flexible wire 24, which is provided at one end with a thrust-head 24^a and at its opposite end engages the thermostat 23. A flexible housing-tube 25

encases the wire 24 and is adapted to be flexed with it, as may be required by the exigencies of installation.

I claim:

1. In a time-controlled gas-burning apparatus, the combination with a gas-burner; of a pilot-light jet therefor; a timing-mechanism constructed and arranged to automatically turn on the supply of gas to the said burner; a yielding stop-member exerting a constant effort to engage a running part of the said timing-mechanism; and a thermostat constructed and arranged to normally hold the said stop-member out of engagement with the timing-mechanism and located adjacent to the said pilot-light jet, so as to be affected by the heat developed thereby, whereby, when the pilot-light becomes extinguished, the automatic turning-on of the gas by the said timing-mechanism will be forestalled and prevented.

2. In a time-controlled gas-burning apparatus, the combination with a gas-burner; of a pilot-light jet therefor; a timing mechanism constructed and arranged to automatically turn on the supply of gas to the said burner; a stop-member normally urged into engagement with a running part of the said timing-mechanism; and a thermostat located adjacent to the said pilot-light jet and constructed and arranged to hold the said stop-member out of engagement with the said timing-mechanism when the said pilot-light jet is lighted; whereby, when the pilot-light jet becomes extinguished, the automatic turning-on of the gas by the said timing-mechanism will be forestalled and prevented.

In testimony whereof, I have signed this specification.

VICTOR M. TYLER.
